Attorney

UNITED STATES PATENT OFFICE.

BURTON H. PARKER, OF DETROIT, MICHIGAN, ASSIGNOR TO TRIMONT MANUFACTURING COMPANY, OF ROXBURY, MASSACHUSETTS, A CORPORATION OF MAINE.

PIPE WRENCH.

Application filed January 24, 1922. Serial No. 531,382.

To all whom it may concern:

Be it known that I, BURTON H. PARKER, a citizen of the United States, residing at Detroit, in the county of Wayne and State of Michigan, have invented an Improvement in Pipe Wrenches, of which the following description, in connection with the accompanying drawings, is a specification, like characters on the drawings representing like parts.

This invention relates to improvements in hand tools of the type in which two jaw members are adapted to engage the work, as in wrenches, pliers, pipe wrenches, etc.

For many uses, hand tools of this general character require a strong grip of the jaws upon the work in order that slippage may not take place. This result is obtainable, of course, by providing the handle with a relatively long leverage, but this in many cases is undesirable in that the length of the movement of the ends of the handle arms increases proportionately to the length of the arms from the pivot point, and as a result a tool of this type having long handle arms can not be readily manipulated with one hand to produce the proper pressure at the jaws. Various attempts have been made to meet this condition by articulated levers and other constructions but the results have not been entirely satisfactory.

One important object of the present invention therefore, is to provide a powerful tool of this general class which is simple in construction, consists of but few parts and which exerts the desired gripping force upon the jaws with a comparatively short leverage, thus producing a tool that is capable of ready manipulation by one hand and at the same time permits the powerful engaging action to be maintained upon the work without requiring heavy pressure application for continued periods on the handle members.

Another important object of the present invention is to provide adjustable means for varying the closing movement imparted to the jaws upon moving the handle members to the closed position.

Still another object of the invention is to provide novel means for imparting pivotal

movement to one jaw by the similar movement of the other jaw.

Other objects of the invention and novel combination of parts will be hereinafter described in connection with the accompanying drawings which show one good practical form of the invention.

In the drawings:

Fig. 1 is a side elevation of a hand tool constructed in accordance with the present invention.

Fig. 2 is a similar view showing one adjustment of the jaws in full lines and a different adjustment of the jaws in dotted lines.

Fig. 3 is a top plan view of Fig. 1; and Figs. 4 and 5 are sectional views taken on the lines 4-4 and 5-5 respectively.

In the drawings, 10 is a head which supports the jaw members 11 and 12. The head may be variously constructed but is shown as of a hollow construction having the spaced side plates 13 and 14 connected by the wall 15. Extending rearwardly from the head 10 is a handle member 16, the same being shown as formed integral with the head 10, and having the hollow construction clearly illustrated in Fig. 5. The construction of the combined head and handle member shown is such that it may be readily blanked out of sheet metal and then bent to form the side plates 13 and 14 and the hollow handle 16. The handle 16 preferably is bent lengthwise slightly in the form of an arc as shown in Figs. 1 and 2, so that the same may be more firmly grasped by the hand.

The construction and shape of the jaw members 11 and 12 may be varied in accordance with the requirements of the field of use for the tool, and in the present instance the jaw members are shown as provided with work engaging teeth 17 and 18. The jaw member 11 is pivotally secured to the head 10 at 19, and the jaw member 12 is supported in spaced relation to the jaw member 11, and is pivotally secured to the head 10 at 20.

In the present device, the construction is such that movement of one jaw towards its closed position serves to impart a similar movement to the other jaw, and to this end the jaw member 12 is provided with a lat-

erally disposed projection 21 that engages an abutment 21^a upon the jaw member 11, and as a result movement of the jaw 11 towards the closed position imparts a similar movement to the jaw 12.

Closing movement is imparted to the jaw member 11 by a handle member 22, in the present instance, having its forward end disposed between the side plates 13 and 14 of the head 10 and pivoted thereto at 22^a. The handle member 22 preferably has a cam face 23 disposed frontwardly of the pivot 22^a, and the jaw member 11 has a rearwardly extending arm 24 adapted to be actuated by the cam face 23.

It is desirable that means be provided for varying the closing movement imparted to the jaws upon moving the pivoted handle member 22 to its closed position, and to this end adjustable means is interposed between the cam face 23 and the arm 24. The adjustable means preferably comprises a threaded member 25 having threaded engagement with the enlargement 26 upon the arm 24, and the member 25 has a head 27 adapted to be grasped by the fingers and rotated to effect adjustment. The head 27 has a face that rests upon the cam face 23, and as the pivoted handle member 22 is rocked from the position shown in full lines in Fig. 2 to the position indicated in dotted lines, the cam face 23 imparts a rocking movement to the jaw 11, and the projection 21 and abutment 21^a impart a similar rocking movement to the jaw 12. The effect upon the jaws produced by adjusting the threaded member 25 is clearly shown in Fig. 2 by the full and dotted line positions of these elements.

It is desirable to provide spring means for yieldingly holding the handle member 22 and the jaws 11 and 12 in the open position, and to this end a spring 28 is provided conveniently coiled about a pin 29 and having one end reacting against a lip 30 of the handle member 22 and the other end reacting against a nose 31 upon the projection 21.

The pins 19, 20, 22^a and 29 are preferably threaded at one end to receive nuts, as shown, for removably securing the pins in place, and as a result of this construction the hand tool may be readily assembled, and should any part become worn or injured, it may be readily removed and replaced by a new part.

From the foregoing description and the drawings, it will be apparent that the pivoted handle member 22 serves to exert a strong gripping force upon the jaws 11 and 12, that the position of the jaws may be readily adjusted to accommodate different size work, and that the entire tool is simple in construction and inexpensive to manufacture. It will also be apparent that the

present device is well adapted for various uses, but because of the powerful gripping force of the jaws and the ease with which they may be adjusted to accommodate work of different size, the present device is particularly well adapted for use as a pipe wrench.

Claims:

1. In a tool having opposing jaws for engaging the work, a head having a handle extending therefrom, a pair of pivoted jaws, each having a pivot pin extending directly through the body of the jaw and into the head for pivotally connecting each jaw to the head, a projection formed integral with each jaw and extending radially from the pivotal mounting of the jaws into overlapping relation, and a handle pivoted to the head and having a cam surface for operating one of the jaws to grip the work. 75

2. In a tool having opposing jaws for engaging the work, a head having a handle extending therefrom, a pair of pivoted jaws, each having a pivot pin extending directly through the body of the jaw and into the head for pivotally connecting each jaw to the head, a projection formed integral with each jaw and extending radially from the pivotal mounting of the jaws into overlapping relation, and a handle pivoted to the head and having a cam surface for operating one of the jaws to grip the work, and a spring acting on the other jaw for opening the jaws. 80

3. In a tool having opposing jaws for engaging the work, a head formed of sheet metal and bent to form a pair of spaced side plates connected by an intermediate portion of the sheet metal, a handle rigid with the head and extending rearwardly therefrom, a pair of jaws mounted between the side plates of the head and pivotally secured to the side plates, a handle extending into the space between said side plates and pivotally secured thereto, cooperating projections upon said jaws for positively imparting the pivotal movement of one jaw to the other, and jaw actuating means including a cam face upon the pivoted handle and an extension upon one of the jaws and adapted to be swung by the cam face. 100

4. In a tool having opposing jaws for engaging the work, a head having side members and a handle formed integrally of a single piece of metal, a pair of jaws, each having a pivot pin extending directly through the body of each jaw and into the side members of the head, a single projection extending from the body of each jaw into overlapping relation and formed integral with each jaw, a handle pivotally mounted in the head and having a cam for operating one of the jaws, and a spring for opening the jaws. 110

5. In a tool having opposing jaws for en- 120

- gaging the work, a head having side members and a handle formed integrally of a single piece of metal, a pair of jaws, each having a pivot pin extending directly through the body of each jaw and into the side members of the head, a single projection extending from the body of each jaw into overlapping relation and formed integral with each jaw, a handle pivotally mounted in the head and having a cam for operating one of the jaws, an adjustable device mounted on the handle operated jaw and engaging the cam, and a spring for opening the jaws.
- 5 6. In a tool having opposing jaws for engaging the work, a head having a handle ex- tending therefrom, a pair of pivoted jaws, each having a pivot pin extending directly through the body of the jaw and into the head for pivotally connecting each jaw to 20 the head, a projection formed integral with each jaw and extending radially from the pivotal mounting of the jaws into overlapping relation, and a handle pivoted to the head and having a cam surface for operating one of the jaws to grip the work, and a spring mounted in the head and bearing upon the radial overlapping projection of the adjacent jaw to open the jaws.
- 10 7. In a tool having opposing jaws for engaging the work, a head having a handle ex- tending therefrom, a pair of pivoted jaws, each having a pivot pin extending directly through the body of the jaw and into the head for pivotally connecting each jaw to 25 the head, a projection formed integral with each jaw and extending radially from the pivotal mounting of the jaws into overlapping relation, and a handle pivoted to the head and having a cam surface for operating one of the jaws to grip the work, and a spring mounted in the head and bearing upon the radial overlapping projection of the adjacent jaw to open the jaws.
- 15 8. In a tool having opposing jaws for engaging the work, a head having a handle ex-

In testimony whereof, I have signed my 30 name to this specification.

BURTON H. PARKER.
